AUDIO AMPLIFIER FOR TELEPHONE HANDSET

John A. Stratman, West Hollywood, Fla., assignor to
Lumidor Products Corporation, Miami, Fla.

Filed Nov. 12, 1969, Ser. No. 20,036

Term of patent 14 years

Int. Cl. D14—03
U.S. Cl. D26—14

FIG. 1 is a side elevational view of an audio amplifier for telephone handset showing my new design;

FIG. 2 is a top plan view taken along the line 2—2 in FIG. 1;

FIG. 3 is a side elevational view taken along the line 3—3 in FIG. 2;

FIG. 4 is a bottom plan view taken along the line 4—4 in FIG. 1;

FIG. 5 is an end view taken along the line 5—5 in FIG. 1; and

FIG. 6 is an end view taken along the line 6—6 in FIG. 1.

I claim:

The ornamental design for an audio amplifier for telephone handset, substantially as shown and described.
